(57) CLAIM

The ornamental design for a bottle, as shown and described.

DESCRIPTION

FIG. 1 is a perspective view of a bottle, showing the present invention;

FIG. 2 is a front view of the bottle shown in FIG. 1.

FIG. 3 is a left side view of the bottle shown in FIG. 1.

FIG. 4 is a top view of the bottle shown in FIG. 1; and,

FIG. 5 is a bottom view of the bottle shown in FIG. 1.

The broken line showing is for illustrative purposes only, and forms no part of the claimed design.
